ADJUSTABLE DOUBLE LOG DOG FOR SAWMILLS

Raymond C. Jurek, Virginia, Minn.

Application February 21, 1956, Serial No. 566,943

7 Claims. (Cl. 143—125)

This invention relates in general to new and useful improvements in sawmill constructions, and more specifically to an improved log dog assembly.

In order that a log may be retained in position during a sawing operation, the head blocks are provided with suitable log dogs for gripping the log and retaining it in position. The log dogs generally include upper and lower dogs which are disposed in opposed relation and which grip the log therebetween. In order to engage the log dogs with the log, it is necessary that the dogs be advanced or retracted away from a knee of the head block depending upon the diameter of the log and also be moved vertical with respect to each other to clamp a log therebetween. Normally this is done manually with the result that it is not only time consuming, but requires considerable work upon the operator of the sawmill. In fact, most installations require the use of one man for operating the sawmill and another man for operating the log dogs.

It is therefore the primary object of this invention to provide an improved log dog assembly which includes a fluid cylinder connected to the log dogs whereby by turning a simple control handle the operator of the sawmill may open or close the log dogs as desired without effort on his part.

Another object of this invention is to provide an improved log dog assembly which includes an upper dog and a lower dog mounted for movement away from and towards each other, there also being provided means connected to the log dogs which permits the simultaneous movement of the log dogs in and out together.

Still another object of this invention is to provide an improved log dog assembly which employs a fluid cylinder which is so constructed whereby it may be easily attached to the knees of existing sawmills.

A further object of this invention is to provide an improved log dog assembly which has an extremely simple control whereby a sawmill operator may operate the log dog with a minimum of effort so that one person may both set the log on the sawmill and operate the sawmill.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is an elevational view of a head block of a sawmill and shows positioned thereon a log, the log being clamped on the head block by means of the log dog assembly which is the subject of this invention;

Figure 2 is a front view of the log dog assembly removed from the head block and shows the specific details thereof;

Figure 3 is a fragmentary elevational view similar to Figure 1 and shows the upper log dog in an elevated position;

Figure 4 is an enlarged transverse vertical sectional view

2

taken through a log dog assembly and shows the specific details of each and every part thereof;

Figure 5 is an enlarged fragmentary horizontal sectional view taken substantially upon the plane indicated by the section line 5—5 of Figure 2 and shows further the details of an operator for moving the log dogs in and out; and

Figure 6 (Sheet 1) is an enlarged fragmentary vertical sectional view taken substantially upon the plane indicated by the section line 6—6 of Figure 5 and shows further the details of the operator for moving the log dogs in and out.

Referring now to Figure 1 in particular, it will be seen that there is illustrated details of a sawmill which includes a head block 10 having adjustably mounted thereon a knee 12. Carried by the knee 12 is the log dog assembly, which is the subject of this invention, the log dog assembly being referred to in general by the reference numeral 14. The log dog assembly 14 is illustrated as gripping a log 16 and retaining it in position on the head block 10.

The log dog assembly 14 includes a mounting bracket which is referred to in general by the reference numeral 18. The mounting bracket 18 is formed of a vertical strap 20 which has secured to the lower end thereof a plate 22. A similar plate 24 is secured to the upper end of the strap 20. The strap 20 is suitably secured to the knee in the position best illustrated in Figure 1.

Referring now to Figure 4 in particular, it will be seen that the plates 22 and 24 are provided with aligned slots 26 and 28, respectively. Slidably received in the slots 26 and 28 for guided movement is a slide bar 30. The slide bar 30 is vertically disposed and has secured to the upper end thereof by means of suitable clamps 32 a cylinder 34 of a fluid motor which is referred to in general by the reference numeral 36. Slidably positioned within the cylinder 34 is a piston 38 which has connected thereto an elongated piston rod 40. The piston rod 40 passes through a bore 42 in the upper plate 24 and is guided relative thereto.

In order that the fluid motor 36 may be controlled, there is provided a valve 44. The valve 44 has connected thereto an air line 46 (Figures 1 and 3) which may be connected to any desired compressed air supply. Extending from the valve 44 and connected to opposite ends of the cylinder 34 are lines 48 and 50. The valve 44 is provided with a suitable handle 52 for operating the same. By selectively positioning the handle 52, the piston 38 is moved up or down in the cylinder 34.

Secured to the lower end of the slide bar 30 for limited movement therewith is a lower dog assembly which is referred to in general by the reference numeral 54. The lower dog assembly 54 includes a lower support 56 (Figure 4) which is secured directly to the slide bar 30. Extending transversely through the lower support 56 is a lower dog 58. The dog 58 includes a rack portion 59 (Figure 1) to facilitate the positioning thereof.

Journalized in the plates 22 and 24 is a vertically extending shaft 60. The shaft 60 is mounted for both rotation and vertical sliding movement. Carried by the lower support 56 is a journal block 62 in which the lower end of the shaft 60 is journalized. Secured on the extreme lower end of the shaft 60 is a gear 64 which is meshed with the rack 60 of the dog 58. By rotating the shaft 60, the rack 59 is driven by the gear 64 with the result that the lower dog 58 is moved in or out as desired with respect to the support 56.

Slidably mounted on the slide bar 30 intermediate the plates 22 and 24 is an upper dog assembly which is referred to in general by the reference numeral 66. The upper dog assembly 66 includes an upper support 68 which is guidingly positioned on the slide bar 30. Se-

cured to the upper support 68 is a pair of ears 70 in which there is positioned the lower end of the piston rod 40. The piston rod 40 is connected to the upper support 68 by means of a collar 72 which is threadedly engaged in a threaded lower portion 74 of the piston rod 40, the collar 72 being disposed between the ears 70.

The shaft 60 also extends through the ears 70 and is suitably journaled therein for both rotation and vertical sliding movement. The shaft 60 also includes an elongated keyway 76. Positioned between the ears 70 and suitably keyed to the shaft 60 is a gear 78. Positioned above the uppermost ear 70 and also keyed to the shaft 60 for vertical sliding movement is a crank 80. The crank 80 includes a latch element 82 which is engaged with a segment ring 84 having a plurality of circumferentially spaced notches 86 for receiving the latch 82. The latch 82 is pivotally mounted on a pivot pin 88 and normally seats in one of the notches 86. In order that the latch 88 may be selectively moved to an inoperative position, there is carried by the crank 80 a sleeve 90 in which there is mounted a spring 92. Disposed within the spring 92 and connected to the latch member 82 is a pin 94 having a button 96 on the upper end thereof. By depressing the button 96, the latch member 82 is moved to an inoperative position and the crank 80 is free to be rotated to rotate the shaft 60 whereby the gears 64 and 78 may be rotated.

Slidably carried by the upper support 68 is an upper dog 98. The upper dog 98 includes a rack portion 100 which is meshed with the gear 78.

In the operation of the log dog assembly 14, a log, such as the log 16, to be sawed is positioned on the head block 10 in abutment with the knee 12. At this time the lower dog 58 and the upper dog 98 are separated, the lower dog 58 being in a lower point of travel out of the way of the log 16 and the upper dog 98 being vertically elevated, as is best illustrated in Figure 3. In the event the dogs 58 and 98 project farther enough away from the knee 12, it will not be necessary to move in or out with respect to the supports 56 and 68. Thus once the log 16 has been pushed against the knee 12, it is merely necessary for the operator of the sawmill to turn the handle 52 to the desired position. This will result in the piston 38 moving downwardly so that the piston rod 40 will also move downwardly to move the upper dog 98 into engagement with the log 16. Once the dog 98 engages the log 16, the downward movement of the piston 38 will substantially stop and as a result the cylinder 34 will move upwardly. This will result in the upward movement of the lower dog 58 to the position illustrated in Figure 1. Further movement of the piston 38 with respect to the cylinder 34 will result in the effective clamping of the log 16. Inasmuch as the operator merely has to turn the handle 52 to position the dogs 58 and 98, it will be readily apparent that the operation of the log dog assembly 14 is extremely simple and requires no hard work on the part of the sawmill operator. After the log 16 has been fully sawed, it is released from the head block 10 by turning the handle 52 in the opposite direction. This will result in the simultaneous upper movement of the piston 38 and the downward movement of the cylinder 34, so as to move the dogs 58 and 98 apart.

In the event a log of a different size from the log 16 is to be mounted on the head block 10, it may be necessary to either advance or retract the dogs 58 and 98. This is accomplished by merely releasing the latch member 82 and rotating the crank 80 in any desired direction. Inasmuch as the crank 80 drives the shaft 60 which in turn drives the two gears 64 and 78, it will be readily apparent that the dogs 58 and 98 are either advanced or retracted simultaneously. Because of the ratio between the gears 64 and 78 and the rack portions 59 and 100, respectively, it will be seen that only a slight

movement of the crank 80 will be necessary to properly position the dogs 58 and 98.

It is pointed out that the dogs 58 and 98 are disposed on the left side of the slide bar 30, as is illustrated in Figure 4. If desired, the gears 64 and 78 may be made smaller or moved further away from the slide bar 30. In such event, the dogs 58 and 98 may be moved to the right of the slide bar 30 if it is so desired.

A resilient stop assembly 102 (Figures 2 and 4) is carried by the plate 24. The stop assembly 102 includes a stop member 104 having a stem 106 slidably passing through the plate 24. A spring 108 is carried by the stem 106. An angle member 110 is carried by the slide bar 30 in alignment with the stop member 104.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A log dog assembly comprising a mounting bracket, a slide bar supported by said mounting bracket for limited vertical sliding movement, an upright fluid motor, said fluid motor including a cylinder secured to an upper end of said slide bar, a piston rod projecting downwardly from said cylinder, a lower dog supported by and for up and down movement with said slide bar at the lower end of said slide bar, an upper dog slidably mounted for vertical movement on said slide bar, said upper dog being connected to said piston rod.

2. A log dog assembly comprising a mounting bracket, a slide bar supported by said mounting bracket for limited vertical sliding movement, an upright fluid motor, said fluid motor including a cylinder secured to an upper end of said slide bar, a piston rod projecting downwardly from said cylinder, a lower dog supported by and for up and down movement with said slide bar at the lower end of said slide bar, an upper dog slidably mounted for vertical movement on said slide bar, said upper dog being connected to said piston rod, control means for said fluid motor mounted on said mounting bracket.

3. A log dog assembly comprising a mounting bracket, a slide bar supported by said mounting bracket for limited vertical sliding movement, an upright fluid motor, said fluid motor including a cylinder secured to an upper end of said slide bar, a piston rod projecting downwardly from said cylinder, a lower dog supported by and for up and down movement with said slide bar at the lower end of said slide bar, an upper dog slidably mounted for vertical movement on said slide bar, said upper dog being connected to said piston rod, means connected to said upper and lower dogs for simultaneously extending and retracting said upper and lower dogs relative to said slide bar.

4. A log dog assembly comprising a mounting bracket, a slide bar supported by said mounting bracket for limited vertical sliding movement, an upright fluid motor, said fluid motor including a cylinder secured to an upper end of said slide bar, a piston rod projecting downwardly from said cylinder, a lower support carried by the lower end of said slide bar, a lower dog carried by said lower support for up and down movement with said slide bar, an upper support carried by said piston rod, said upper support being vertically slidably mounted on said slide bar, an upper dog carried by said upper support, means connected to said upper and lower dogs for simultaneously extending and retracting said upper and lower dogs relative to said upper and lower supports and said slide bar.

5. A log dog assembly comprising a mounting bracket, a slide bar supported by said mounting bracket for limited

vertical sliding movement, an upright fluid motor, said fluid motor including a cylinder secured to an upper end of said slide bar, a piston rod projecting downwardly from said cylinder, a lower support carried by the lower end of said slide bar, a lower dog carried by said lower support for up and down movement with said slide bar, an upper support carried by said piston rod, said upper support being vertically slidably mounted on said slide bar, an upper dog carried by said upper support, means connected to said upper and lower dogs for simultaneously extending and retracting said upper and lower dogs relative to said upper and lower supports and said slide bar, said means including racks on said upper and lower dogs, a shaft carried by said mounting bracket for rotation and vertical sliding movement, gears connected to said shaft for rotation with said shaft, said gears being meshed with said racks.

6. A log dog assembly comprising a mounting bracket, a slide bar supported by said mounting bracket for limited vertical sliding movement, an upright fluid motor, said fluid motor including a cylinder secured to an upper end of said slide bar, a piston rod projecting downwardly from said cylinder, a lower support carried by the lower end of said slide bar, a lower dog carried by said lower support for up and down movement with said slide bar, an upper support carried by said piston rod, said upper support being vertically slidably mounted on said slide bar, an upper dog carried by said upper support, means connected to said upper and lower dogs for simultaneously extending and retracting said upper and lower dogs relative to said upper and lower supports and said slide bar, said means including racks on said upper and lower dogs, a shaft carried by said mounting bracket for rotation and vertical sliding movement, gears connected to said shaft for rotation with said shaft, said gears being meshed

30
35

with said racks, one of said gears being retained by said upper support for movement therewith, said one gear being keyed on said shaft for relative sliding movement.

7. A log dog assembly comprising a mounting bracket, a slide bar supported on said mounting bracket for limited vertical sliding movement, an upright fluid motor, said fluid motor including a cylinder secured to an upper end of said slide bar, a piston rod projecting downwardly from said cylinder, a lower support carried by the lower end of said slide bar, a lower dog carried by said lower support for up and down movement with said slide bar, an upper support carried by said piston rod, said upper support being vertically slidably mounted on said slide bar, an upper dog carried by said upper support, means connected to said upper and lower dogs for simultaneously extending and retracting said upper and lower dogs relative to said upper and lower supports and said slide bar, said means including racks on said upper and lower dogs, a shaft carried by said mounting bracket for rotation and vertical sliding movement, gears connected to said shaft for rotation with said shaft, said gears being meshed with said racks, one of said gears being retained by said upper support for movement therewith, said one gear being keyed on said shaft for relative sliding movement, drive means for said shaft supported by said upper support.
